TAPE CARTRIDGE

William A. Sours, Sauquoit, N.Y., assignor to Cogar Corporation, Wappingers Falls, N.Y.

Filed Jan. 8, 1970, Ser. No. 105,147

Term of patent 14 years

Int. Cl. D14—02

U.S. Cl. D26—14

FIG. 1

FIG. 2

FIG. 3

FIG. 1 is a side perspective view of a tape cartridge, showing my new design;

FIG. 2 is a back perspective view of the tape cartridge shown in FIG. 1; and

FIG. 3 is a side elevational view of the tape cartridge of FIG. 1 taken on the line 3—3 of FIG. 1 in the direction of the arrow.

I claim:

The ornamental design for a tape cartridge, as shown.
